[57] **CLAIM**

The ornamental design for an adjustable rack for supporting articles being spray-painted, as shown and described.

DESCRIPTION

FIG. 1 is a front elevational view of an adjustable rack for supporting articles being spray-painted showing my new design;

FIG. 2 is a right side elevational view thereof, the left side being a mirror image of that shown;

FIG. 3 is a bottom plan view thereof;

FIG. 4 is a top plan view thereof;

FIG. 5 is a rear elevational view thereof; and

FIG. 6 is an enlarged fragmentary vertical cross-sectional view thereof, taken along line 6—6 of FIG. 1".
